TURBINE PEDESTAL ARRANGEMENT

Ozro N. Bryant, Prospect Park, Pa., assignor to
Westinghouse Electric Corporation, East Pittsburgh, Pa., a corporation of Pennsylvania

Application May 2, 1947, Serial No. 745,421

2 Claims. (Cl. 253—39)

1

The invention relates to elastic-fluid turbines and it has for an object to provide an improved pedestal and bearing construction for the high-pressure end of such apparatus.

It is common turbine practice to have a low-pressure end of the cylinder attached to the foundation or bed plate, to provide a pedestal on the high-pressure end of the cylinder and keyed to the foundation for axial movement relative to the latter, to have the rotor carried by a low-pressure end bearing at the low-pressure end of the cylinder and by a high-pressure end bearing connected to the pedestal and arranged to carry radial and thrust loads imposed thereon by the rotor and to have the high-pressure end of the cylinder supported on and connected to the pedestal by means providing for movement of the cylinder and the pedestal axially together while accommodating for radial expansion of the cylinder with the cylinder axis held vertically and horizontally.

A further object of the invention is to provide said arrangement of apparatus wherein the pedestal includes a platform carrying the high-pressure end bearing, supporting the high-pressure end of the cylinder, and connected to the latter, and wherein the pedestal also includes a plurality of vertical plates which hold the cylinder axis vertically and horizontally and which are elastically deformable axially to accommodate for axial expansion of the rotor and cylinder, thereby making it possible to attach the lower end of the pedestal to the foundation without the use of key means providing for axial movement of the pedestal as a whole.

These and other objects are effected by the invention as will be apparent from the following description and claims taken in connection with the accompanying drawings, forming a part of this application, in which:

Fig. 1 is a side elevational view of a turbine having the improved pedestal applied thereto;

Fig. 2 is a fragmentary view, partly in section, and showing the pedestal structure in greater detail;

Fig. 3 is a sectional view taken along the line III—III of Fig. 2; and

Fig. 4 is a view similar to Fig. 3 but showing a modified arrangement of column structures for supporting the high-pressure end of the turbine cylinder.

In the drawings, there is shown a foundation or bed plate 10 carrying the turbine cylinder 11 and a pedestal construction, at 12. The cylinder encloses a rotor 14 carried by bearings 15 and

2

16, the bearing 15 being supported by the low-pressure end of the cylinder and the bearing 16 being carried by the pedestal construction, at 12.

The bearing 16 is connected to the pedestal construction, at 12, so that its center is held axially, vertically and horizontally relative to the pedestal and so that it may move angularly about such center to maintain its alignment relative to the rotor.

10 The pedestal, at 12, includes a horizontal platform 18 supported by the vertical plates 19, which have their lower ends or edges connected to and carried by the foundation structure 10, the plates extending in normal transverse relation with respect to the rotor axis so as to be elastically deformable axially while having stiffness which is effective to hold the rotor axis both vertically and horizontally.

As shown, the bearing 16 is of the combined 20 radial and thrust type, it including a housing 20 having mounted therein the radial or sleeve bearing bushing 21 cooperating with the rotor journal 22. The journal has spaced collars 23 between 25 which the bushing 21 is located, the thrust bearing elements 24 and 25 being disposed between the respective collars and ends of the bushing.

With this combined arrangement of radial and thrust bearing, it is essential that the housing 20 be supported or carried in such manner that it may tilt to accommodate for misalignment while being effective to hold the center of the bearing against displacement axially, vertically or horizontally. While the bearing housing may be supported from the platform by any suitable means 30 serving these purposes, preferably, as disclosed and claimed in my application Serial No. 727,134, filed February 7, 1947 and now Patent 2,524,693 dated October 3, 1950, as shown, the housing is carried by a transverse, flexible plate 27 and by 35 a conical arrangement of bars or spoke members 28, the plate 27 and the bars or spoke members 28 being connected to the housing so as to be disposed radially with respect to the center o of the bearing. The lower edge of the plate 27 and the lower ends of the rods or bars 28 are connected 40 in any suitable manner to the platform 18. It will be apparent, therefore, that plate 27 and the rods or bars 28 are elastically deformable in axial planes of the bearing and tangentially in relation to the bearing center, this arrangement or relation providing for angular movement of the bearing housing in any direction to maintain alignment of the bearing with the rotor.

45 With a vertically-disposed and transversely extending plate, for example, the plate 27, such 50

55

plate is elastically deformable not only to accommodate for angular movement of the bearing housing for maintenance of alignment but also, unless resisted, it would permit of movement of the housing axially, while its stiffness is effective to hold the rotor axis both vertically and horizontally. As the spokes or bars 28 are arranged as a conical group with each spoke or bar radiating from the common center o, it will be apparent that, while each rod or bar is elastically deformable to permit of movement of the bearing housing in axial planes and in directions which are tangential with respect to the center, nevertheless, each rod or bar has stiffness which is effective both axially and radially, the axial component being effective to prevent axial movement of the thrust bearing housing relative to the platform and therefore of the bearing center and the radial component cooperating with the plate 27 to hold the bearing housing vertically and horizontally while permitting of angular movement thereof for alignment purposes.

The high-pressure end 30 of the turbine cylinder is provided with extensions or pads 31 at each side, the extensions or pads bearing on the upper ends of column structures 32a in Figures 1, 2, and 3 and 32b in Figure 4. The column structures 32a are of cruciform section so as to be stiff laterally in all directions and the lower ends thereof are connected, as by welding, to the upper side of the platform 18. The upper ends of the column structures are connected to the cylinder pads by means which accommodates for sliding movement of the pads on the column structures sufficient to accommodate for expansion of the cylinder so as to accommodate for expansion, particularly radial expansion horizontally of the cylinder.

The high-pressure end of the turbine cylinder is connected to the pedestal structure, at 12, by means of a thrust and tie connection, at 34, the latter preferably being comprised by a horizontal plate element 35 connected, at 36, to the turbine cylinder and, at 37, to the adjacent edge of the platform 18.

From the construction so far described, it will be apparent that the pedestal structure, at 12, is capable of moving with the turbine cylinder axially, such axial movement relative to the foundation being permitted by the supporting plates 19, which, as they extend normally in transverse relation to the rotor axis, are elastically deformable axially while their stiffness is effective to hold the platform both horizontally and vertically with respect to the foundation and they, therefore, function to hold the bearing both vertically and horizontally. As the bearing housing is carried by members which are elastically deformable in axial planes and in directions which are tangential with respect to the center of the bearing, it will be apparent that the bearing center will be held axially, vertically and horizontally with respect to the platform while the bearing housing is permitted to tilt about the bearing center in any direction to avoid misalignment. As the thrust and tie connection plate 35 is disposed horizontally, it will be apparent that it is elastically deformable vertically to accommodate for radial expansion of the cylinder vertically while its stiffness is effective both axially and transversely, the transverse stiffness serving to hold the cylinder axis horizontally. The horizontal plate 35 and the supporting column structures 32a for the cylinder pads therefore cooperate to accommodate for radial expansion of

the cylinder both vertically and horizontally while they are effective to hold the cylinder axis both vertically and horizontally. It is to be understood that the inclined spoke members 28 are merely one example of means for anchoring the thrust bearing to the platform to prevent relative axial movement of the spindle and the cylinder at the high pressure end of the turbine. Any other suitable means connecting the thrust bearing to the platform for this purpose with provision for the accommodation of angular movement of the bearing sleeve to maintain the latter aligned with the rotor journal may be used. As the bearing housing is also held both vertically and horizontally, it will be apparent that the pedestal structure, at 12 and the features associated therewith are responsible for holding both the cylinder and the rotor vertically and horizontally.

In Figure 4, instead of the cylinder pads 31b having clearance with respect to hold-down bolts, as is the case with the pads 31 with respect to the hold-down bolts 33 in Figures 1, 2 and 3, in Figure 4, the pads 31b are fastened in fixed relation to the upper ends of the column structure 32b, the lower ends of the latter being attached to the platform 18. Each column structure 32b is shown as being comprised by a pair of vertically-disposed plates 39 which extend in parallel relation to the rotor axis. Therefore, while the plates 39 are stiff so as to connect the high-pressure end of the cylinder and the pedestal structure for axial movement together, nevertheless, they are elastically deformable radially to accommodate for radial expansion of the cylinder horizontally.

While the invention has been shown in several forms, it will be obvious to those skilled in the art that it is not so limited, but is susceptible of various other changes and modifications without departing from the spirit thereof.

What is claimed is:

1. In a turbine, wherein a foundation carries a cylinder enclosing a rotor, a pedestal structure carried by the foundation adjacent to the high pressure end of the cylinder; said pedestal structure including a horizontal platform; bearing means carrying radial and thrust loads imposed thereon by the rotor; means for connecting the bearing means to the platform so that the center of the bearing means is held against vertical, horizontal and axial movements with respect to the platform while it is movable angularly in all directions with respect to said center to maintain alignment of the bearing with the rotor; means for supporting the weight of the high-pressure end of the cylinder on the platform and accommodating for radial expansion of the cylinder horizontally; and a plate connected to the high-pressure end of the cylinder and to the platform; said plate being horizontal so as to be elastically deformable vertically to accommodate for vertical expansion of the cylinder and so as to be stiff horizontally to hold the cylinder axis horizontally with respect to the platform; said pedestal structure also including vertical plates for supporting the platform from the foundation and which plates extend normally with respect to the rotor axis so as to be elastically deformable axially of the turbine to accommodate for axial expansion and contraction of the rotor and cylinder and to be stiff transversely of the rotor axis to hold the latter against transverse displacement vertically and horizontally.
2. In a turbine wherein a foundation carries a cylinder enclosing a rotor, a pedestal structure

75

carried by the foundation adjacent to the high-pressure end of the cylinder; said pedestal structure including a horizontal platform; a bearing carrying radial and thrust loads imposed thereon by the rotor; means for connecting the bearing to the platform so that the center of the bearing is held vertically and horizontally with respect to the platform while it is movable angularly in all directions with respect to said center to maintain alignment of the bearing with the 10 rotor; vertical column structures carried by the platform and spaced outwardly from each side of the rotor axis; supporting pads unitary with the high-pressure end of the cylinder and bearing on and connected to the column structure; said column structures each including one or more plates extending vertically and parallel to the rotor axis so as to be elastically deformable horizontally; and a plate connected to the high-pressure end of the cylinder; said plate being 20 horizontal so as to be elastically deformable vertically to accommodate for vertical expansion of the cylinder and so as to be stiff horizontally to

hold the cylinder axis horizontal with respect to the platform, said pedestal structure also including vertical plates for supporting the platform from the foundation and which plates extend normally with respect to the rotor axis so as to be elastically deformable axially of the turbine to accommodate for axial expansion and contraction of the rotor and cylinder and to be stiff transversely of the rotor axis to hold the latter against transverse displacement vertically and horizontally.
